DESIGN FOR A WRENCH

Francis A. Snell, Chenango Forks, N. Y., assignor
to Botnick Motor Corporation, Binghamton,
N. Y.

Application September 14, 1945, Serial No. 122,083

Term of patent 14 years

(Cl. D54—16)

To all whom it may concern:

Be it known that I, Francis A. Snell, a citizen of the United States of America and resident of the city of Chenango Forks, county of Broome, and State of New York, have invented a new, original, and ornamental Design for a Wrench, of which the following is a specification, reference being had to the accompanying drawing, forming a part thereof, in which:

Fig. 1 is a side elevation of a wrench showing my new design;

Fig. 2 is a front view of the same; and
Fig. 3 is a top plan view of the same.

I claim:

The ornamental design for a wrench, substantially as shown.

FRANCIS A. SNELL.
